PHASE MODULATION DETECTION

Lowell E. Norton, Princeton, N. J., assignor to
 Radio Corporation of America, a corporation of
 Delaware

Application May 22, 1943, Serial No. 488,018

3 Claims. (Cl. 250—20)

This invention relates to phase modulation detection, and more particularly to the detection of phase modulation in which the time rate of change of phase is very low as compared to carrier frequency so that frequency selective circuits are incapable of providing detection.

Ordinarily the time rate of change of phase in phase modulation systems is large enough as compared to the carrier frequency so as to provide an appreciable frequency shift, and high "Q" selective circuits or discriminators may be used for detection. However, in certain applications, for example direction finders of the type described in copending U. S. application Ser. No. 487,678, filed by L. E. Norton on May 20, 1943, it is necessary to detect phase modulation which comprises a small shift in phase of a relatively high frequency carrier at a very low modulation frequency.

It is the principal object of this invention to provide a method of and means for detecting small phase shifts in a relatively high frequency carrier which is modulated at a low frequency.

This and other objects will become apparent to those skilled in the art upon consideration of the following description, with reference to the accompanying drawings, of which:

Fig. 1 is a schematic block diagram of a phase detector system according to the instant invention.

Fig. 2 is a schematic block diagram of a modification of Fig. 1.

Fig. 3 is a schematic circuit diagram of a balanced modulator of the type employed in the circuits of Figs. 1 and 2, and

Fig. 4 is a schematic circuit diagram of a modulator also employed in the circuits of Figs. 1 and 2.

Referring to Fig. 1, a radio frequency amplifier 1 is connected through a modulator 3 to a filter 5 and thence through an automatic frequency control circuit 15 to a radio frequency oscillator 7. The oscillator is arranged for variable frequency operation, and is connected to a balanced modulator 9. The tuning of both the amplifier 1 and the oscillator 7 may be varied manually. The two controls are mechanically ganged, as indicated by the dash line 11. The oscillator 7 is arranged so that its frequency may

be varied over a relatively narrow range by variations in the magnitude of a D.-C. control voltage applied thereto.

An oscillator 13 arranged to operate at a fixed intermediate frequency is coupled to the balanced modulator 9. The output of the balanced modulator 9 is applied to the modulator 3. The filter 5 is tuned to pass the frequency of the IF oscillator 13. The automatic frequency control circuit 15, which is connected to the output of the filter 5, is also connected to the oscillator 13 through a -90° phase shifter 17. The D.-C. output of the automatic frequency control circuit 15 is applied to the frequency control input circuit of the oscillator 7.

A detector 19 comprising a diode rectifier or the like is coupled through resistors 21 and 23 to the output circuits of the IF filter 5 and the IF oscillator 13, respectively. A resistor 25 is shunted across the input circuit of the detector 19. The resistance of the resistor 25 is much lower than that of the resistors 21 and 23.

The operation of the above described system is as follows:

The tuning controls of the amplifier 1 and the oscillator 7 are adjusted to the carrier frequency of a phase modulated signal applied to the input of the amplifier 1. The phase modulated carrier may be represented by the expression $e_0 = \sin [\omega t - \psi f(t)]$ in which $\omega/2\pi$ is the carrier frequency. The oscillator 7 will operate initially at a frequency $\omega_0/2\pi$, approximately equal to the carrier frequency $\omega/2\pi$.

Designating the frequency of the operation of the IF oscillator 13 as $\alpha/2\pi$, voltages

$$e_1 = E_1(1 + m_1 \cos \alpha t)$$

and $e_2 = E_1(1 - m_1 \cos \alpha t)$ produced thereby are applied to the balanced modulator 9. Voltages $e_3 = E_3(1 + m_2 \cos \omega_0 t)$ and $e_4 = E_3(1 - m_2 \cos \omega_0 t)$ from the oscillator 13 are also applied to the balanced modulator 9. The resulting output from the balanced modulator 9 is

$$e_5 = 2E_1E_3k \left[1 + \frac{m_1m_2}{2} \cos (\omega_0 - \alpha)t + \frac{m_1m_2}{2} \cos (\omega_0 + \alpha)t \right]$$

This may be rewritten as:

$$e_5 = E_5 \{ [1 + m_2 \cos (\omega_0 - \alpha)t] + [1 + m_2 \cos (\omega_0 + \alpha)t] \}$$

The voltage e_5 from the balanced modulator 9 and the voltage e_6 from the RF amplifier 1 are applied to the modulator 3, as shown in Fig. 4.

The resulting output from the modulator 3 is

$$e_6 = k_1 E E_5 \left[1 + m_3 \cos(\omega_0 - \alpha)t + m_3 \cos(\omega_0 + \alpha)t + m \sin[\omega t - \psi f(t)] + \frac{mm_3}{2} \sin[(\omega + \omega_0 + \alpha)t - \psi f(t)] + \frac{mm_3}{2} \sin[(\omega + \omega_0 - \alpha)t - \psi f(t)] + \frac{mm_3}{2} \sin[(\omega - \omega_0 + \alpha)t - \psi f(t)] - \frac{mm_3}{2} \sin[(\omega - \omega_0 - \alpha)t + \psi f(t)] \right]$$

The voltage e_6 is applied to the filter 5 which is turned to pass the frequency $\alpha/2\pi$. The output of the filter 5 is

$$e'_6 = k_2 E E_5 \left[1 + \frac{mm_3}{2} \sin[(\omega - \omega_0 + \alpha)t - \psi f(t)] - \frac{mm_3}{2} \sin[(\omega_0 - \omega + \alpha)t + \psi f(t)] \right]$$

The voltage e'_6 is applied to automatic frequency control circuit 15. The output of the IF oscillator 13 is applied through the -90° phase shifter 17 to the automatic frequency circuit 15 where it is compared with the voltage e'_6 to produce a D.-C. control voltage output which is proportional in magnitude and related in polarity to the difference in frequency of the two inputs. The control voltage from the automatic frequency control circuit 15 tunes the oscillator 7 to a frequency exactly equal to that of the input to the amplifier 1 so that $\omega_0 = \omega$. The output voltage from the filter 5 then becomes

$$e''_6 = k_2 E E_5 \left[1 + \frac{mm_3}{2} \sin[\alpha t - \psi f(t)] - \frac{mm_3}{2} \sin[\alpha t + \psi f(t)] \right] = k_2 E E_5 \{ 1 - 2mm_3 \sin[\psi f(t)] \cos \alpha t \}$$

The voltage e''_6 may be written for convenience as $k_3 E_6 \{ 1 + m_3 \sin[\psi f(t)] \cos \alpha t \}$.

The output voltage of the IF oscillator 13 may be represented as $e'_1 = E_1 \cos \alpha t$. This voltage is combined with the voltage e''_6 in the resistor 25. Denoting the resistance of the resistors 21, 23 and 25 as R_1 , R_2 and R_3 respectively, the voltage across R_3 is

$$\frac{R_3}{R_1 + R_3} e''_6 + \frac{R_3}{R_2 + R_3} e'_1$$

and is of the form

$$e_7 = E_7 \{ 1 + m_7 \sin[\psi f(t)] \cos \alpha t \}$$

where the modulation factor m_7 is determined by the relative sizes of R_1 and R_2 . The voltage e_7 is applied to the detector 19, providing an output including a voltage

$$e_8 = E_8 \sin[\psi f(t)]$$

where $\psi f(t)$ is the original phase modulation of the carrier frequency $\omega/2\pi$. If the phase modulation is small so that the departure of $\sin[\psi f(t)]$ from $[\psi f(t)]$ is small, then e_8 is approximately equal to $E_8 (\psi f(t))$. Thus the output of the detector 19 corresponds to the original phase modulation.

Fig. 2 shows a modified circuit in which the detector 19 and the combining network 21, 23, 25 are replaced by a modulator 119. The portions of the circuit of Fig. 2, which are similar to corresponding elements of Fig. 1, are indicated by similar reference numerals. The method of controlling the frequency of the radio frequency oscillator 7 is the same as that used in the system of Fig. 1, and the modulator 3, filter 5, oscillator 13 and automatic frequency control circuit 15 perform as in the circuit of Fig. 1. In this case, detection is accomplished by applying the output of the radio frequency amplifier 1 and that of the oscillator 7 to the modulator 119, which is similar to the modulator 3 but provided with a capacitor shunted across its output circuit to remove voltages of carrier and higher

frequencies. When the frequency of the oscillator 7 is equal to that of the input voltage ($\omega_0 = \omega$), the output from the modulator 119 corresponds to the original phase modulation, pro-

vided as before that $\psi f(t)$ does not depart appreciably from $\sin[\psi f(t)]$.

Referring to Fig. 3, a suitable circuit for the

balanced modulator 9 of Figs. 1 and 2 comprises a pair of multi-grid convertor type tubes 22 and 24, such as RCA 6L7's. One input is applied through a transformer 26 in push-pull to the inner control grids 27 and 29 of the tubes 22 and 24. The other input is applied through a transformer 31 in push-pull to the outer control grids 33 and 35 of the tubes 22 and 24. The anodes of the tubes 22 and 24 are connected together through a common load resistor 37 to a D.-C. source 39. Self-bias is provided by a common cathode resistor 41, by-passed by a capacitor 43.

Screen potentials are provided from the source 39 through a voltage dropping resistor 45.

Fig. 4 shows a circuit suitable for the modulators 3 and 119 of Figs. 1 and 2. A multi-grid convertor tube 47, similar to the tubes 22 and 24 of the system of Fig. 3 is connected for application of one input voltage to the inner control grid 49. The other input voltage is applied to the outer control grid 51. A D.-C. source 55 is connected to the anode of the tube 49 through a load resistor 53. The modulation products of the two inputs appear across the load resistor 53.

Thus the invention has been described as a method of phase detection capable of providing response to low frequency, low rate, phase modulation of a high frequency carrier. A local unmodulated oscillator is arranged to be automatically maintained in operation at the frequency of the phase modulated carrier by means of an automatic frequency control circuit arranged to respond to the output of a balanced modulator. The output of the local oscillator is compared with the modulated carrier to provide a voltage corresponding to the original phase modulation.

I claim as my invention:

1. A method of detecting phase modulation of a high frequency carrier comprising the steps of locally generating a voltage equal in frequency to the frequency of said carrier, locally generating a second voltage of intermediate frequency, combining said locally generated voltages to provide modulation products, modulating said phase modulated carrier with said modulation products to provide a second group of modulation products, filtering said second group of modulation products to remove therefrom all components having frequencies equal to and higher than said carrier frequency, additively combining said filtered modulation products with said locally generated voltage of intermediate frequency, and rectifying the resultant of said additive combination.

2. The invention as set forth in claim 1, in-

cluding the method of controlling the frequency of said locally generated high frequency voltage which comprises the steps of combining said filtered modulation components with said locally generated intermediate frequency voltage to produce a direct current voltage related in magnitude and polarity to the difference in frequency of said combined voltages, and controlling the frequency of said locally generated high frequency voltage in response to said direct current voltage.

3. A system for detecting phase modulation of a high frequency carrier, including a local high frequency oscillator, a local intermediate frequency oscillator, a balanced modulator including two input circuits connected respectively to said oscillators, and an output circuit, a second modulator connected to said output circuit to

5 modulate said carrier with the output of said balanced modulator, filter means connected to said second modulator and arranged to pass the intermediate frequency components of the output thereof, an automatic frequency control circuit connected to said filter and to said intermediate frequency oscillator to provide a direct current output related in magnitude and polarity to the difference in frequency of the inputs to said automatic frequency control circuit, means for applying said direct current voltage to said local high frequency oscillator to control the frequency of operation thereof, a rectifier, and means for applying the output of said filter and the output of said intermediate frequency oscillator additively to said rectifier.

LOWELL E. NORTON.
